UNITED STATES PATENT OFFICE.

FRANK J. LIESKE, OF DETROIT, MICHIGAN, ASSIGNOR, BY DIRECT AND MESNE ASSIGNMENTS, OF ONE-SIXTEENTH TO CHAS. F. KUHN AND ONE-SIXTEENTH TO H. J. KOEPP, BOTH OF MARQUETTE, MICHIGAN, AND THREE-EIGHTHS TO AMERICAN ENGINEERING ASSOCIATES, A TRUST ESTATE OF MICHIGAN.

SUBMARINE.

1,300,744.

Specification of Letters Patent. Patented Apr. 15, 1919.

Application filed June 23, 1917. Serial No. 176,465.

To all whom it may concern:

Be it known that I, FRANK J. LIESKE, a citizen of the United States, residing at Detroit, county of Wayne, State of Michigan, have invented a certain new and useful Improvement in Submarines, and declare the following to be a full, clear, and exact description of the same, such as will enable others skilled in the art to which it pertains to make and use the same, reference being had to the accompanying drawings, which form a part of this specification.

This invention relates to submarines, and its object is a submarine so arranged as to allow the inmates thereof to escape in case of the submarine sinking. Another object of the invention is a main submarine provided with a slip at the rear end adapted to receive a complete auxiliary submarine. An additional object of the invention is an auxiliary submarine provided with means for securing it in the slip in the main submarine, the device being so arranged as to not change the general outline of the main submarine. These and other objects and the several novel features of the invention in its preferred form are hereinafter more fully described and claimed and shown in the accompanying drawings in which—

30 Figure 1 is an elevation of a submarine embodying my invention.

Fig. 2 is a longitudinal section thereof.

Fig. 3 is an elevation of the auxiliary submarine.

35 Fig. 4 is a longitudinal section thereof.

Fig. 5 is an elevation of the stern of the auxiliary submarine.

40 Fig. 6 is a perspective view of the connecting member between the auxiliary submarine and the main submarine.

Fig. 7 is a section through the submarines taken on line $y-y$ of Fig. 3 showing the position of the auxiliary submarine in the main submarine.

45 Fig. 8 is a cross section of the submarine taken on line $x-x$ of Fig. 3 with the auxiliary submarine in the slip on the main submarine.

50 Fig. 9 is a section through the main submarine taken on line $x-x$ of Fig. 8 showing in disengaged position, means for holding

the auxiliary submarine from movement within the main submarine.

Similar characters refer to similar parts throughout the drawings and specification. 55

The main submarine as shown in Fig. 1 is of the well known type, and is provided with the usual periscope 1 and conning tower 2 which gives access to and from the main submarine. At the forward end the submarine 60 is provided with torpedo tubes 3 and torpedoes therefor as is the usual practice. While the boat may be driven by any of the several well known mechanisms, I have shown an internal combustion engine 4 which propels 65 the boat and generates electricity by means of the generator 5. Tanks 6 are placed at desirable points within the hull of the main submarine and are adapted to be filled with water, for submerging the main submarine 70 or by expelling the water from the tanks the submarine is made to rise.

The auxiliary submarine 8 which is carried by the main submarine is also provided with a means of propulsion (an internal 75 combustion engine being shown), and is provided with a tube 9 at the forward end thereof which is of sufficient size to receive a torpedo and is used as an entrance to the auxiliary submarine, the auxiliary submarine being shown more particularly in Figs. 3 and 4. While I have shown the auxiliary submarine as used with a main submarine it may also be used in connection with a freight boat or warship or other boat in conjunction 85 with which a small submarine is useful. This auxiliary submarine is provided with water tight portlights 10 and is a miniature model of the main submarine, being provided with submerging tanks and other appendages of the larger boat (though not here shown). As will be seen more particularly in Fig. 2, the auxiliary submarine is adapted to fit tightly in the slip 11 of the main submarine, the tube 9 thereon fitting 95 an aperture therefor in the main submarine and the joint between the main and auxiliary submarines being packed to prevent leakage of water. It will also be seen when the auxiliary submarine is setting mines or 100 disconnected from the main submarine water would flow into the main submarine through

the aperture normally filled by the nose 9 of the auxiliary submarine. To close this opening a cylindrical block 12 is provided adapted to be forced into the opening by the 5 hand wheel 13 on the screw shaft 14.

When the auxiliary submarine is in place on the main submarine, the block 12 may be withdrawn from the opening, allowing unobstructed access to the interior of the auxiliary which in this relationship becomes in 10 fact a compartment of the main submarine.

Upon return the auxiliary submarine moves into the slip 11 and a hooked engaging member 15 which protrudes as shown in 15 dotted lines in Fig. 3, engages over the hook member 16 of the main submarine.

The auxiliary submarine is drawn forward in the slip 11 by means of the mechanism shown in the auxiliary submarine 20 and which consists of a motor 17 adapted to drive the shaft 18 through the belt 19 and thus turn the gear 20 on the shaft 18, the gear 20 being in mesh with the gear 21 threaded on the shaft 22 of the hooked 25 engaging member 15. This gear 21 thus acts as a nut and as it is turned the auxiliary submarine is drawn forward until the nose 9 engages tightly in the aperture therefor in the main submarine at which time the 30 hooked engaging member 15 has been drawn up and assumes the position shown in full lines in Figs. 2, 3 and 4. To keep the shaft 22 and engaging member 15 from turning with the gear 21 a keyway is provided in 35 the said shaft as is shown in Fig. 6. It can thus be seen that by placing a suitable key in the keyway the shaft is held from rotation and the engaging member is held in proper alinement.

40 As will be noted more particularly in Fig. 3 the auxiliary submarine is provided with a flange 23 thereon having undercut lugs 24. The method of under-cutting the lugs is shown more particularly in Fig. 7. The 45 main submarine is provided with lugs 25 thereon having hooked ends adapted to engage under the lugs 24 of the auxiliary submarine. The keel of the auxiliary submarine as shown in Fig. 3 is provided with lugs 50 26 thereon which are adapted to engage under similar lugs 27 on the main submarine in the same manner as the lugs 24 and 25 engage. As is shown more particularly in Fig. 9, as the auxiliary submarine settles 55 into the slip on the main submarine, the undercut lugs 24 move in between the lugs 25 on the main submarine, and as the auxiliary submarine is drawn forward the lugs 24 and 25 engage and prevent movement of 60 the auxiliary submarine in relation to the main submarine. The lugs 26 on the keel of the auxiliary submarine are adapted to operate in the same manner, the lugs 26 passing between the lugs 27 as the auxiliary 65 submarine settles into the slip 11 on the

main submarine, and as the auxiliary submarine is drawn forward in the slip 11 the lugs 26 engage beneath the lugs 27 and tend to further prevent motion of the auxiliary submarine in relation to the main submarine. 70

The flange 23 and lugs 24 on the auxiliary submarine and lugs 25 and 27 on the main submarine have the general characteristic of ways and for the sake of brevity the lugs 25 75 and 27 of the main submarine are herein-after termed "ways" and the similar lugs on the auxiliary submarine are termed "complementary ways" and these may be of any well known character of construction by 80 means of which the auxiliary, upon longitudinal movement into the slip, may be locked from vertical movement therein.

It is to be understood that the auxiliary submarine moves into the slip 11 on the 85 main submarine in the same manner as a ferry boat moves into its slip and the main submarine can be moved about to receive the auxiliary submarine by the vertical and horizontal propellers 30 and 31 which may be 90 used to raise or lower the rear end of the main submarine or turn it about on a pivot.

The novel features of this invention exist in providing the well known type of submarine with a life boat which gives the passengers on the submarine an opportunity of escaping if the main submarine is disabled by an enemy shell or by accident. For instance, if the main submarine is struck by a shell and sinks, the passengers of the main 100 submarine may withdraw the closure 12 should the closure be in closed position, from the nose 9 of the auxiliary submarine by turning the hand wheel 13 and the passengers or crew would then open the water 105 tight door 28 of the auxiliary submarine and pass into the interior thereof. The water tight door 28 may then be closed and the motor 17 set into operation forcing the auxiliary submarine backward and disengaging the lugs 24 and 25 at the sides of the auxiliary submarine. This will also disengage the lugs 26 and 27 on the keel thereof, whereupon by exhausting the water 110 from the tanks of the auxiliary submarine, (not here shown) the auxiliary submarine will float free from the main submarine and can then be guided to any point at will, for instance, the auxiliary submarine could then by use of the torpedo and tube 9 sink the 115 ship which blew up the main submarine. 120

The auxiliary submarine may also be used for laying mines as it can be operated more easily than the main submarine, and the auxiliary submarine may use the main submarine as a base and do scouting work and perform such other service not requiring the use of the main submarine. 125

From the foregoing brief description it becomes evident that the device is of use 130

in the saving of life and when in place in the water the main submarine presents a smooth contour to the water, and thus does not retard movement of the main submarine 5 through the water.

Having thus briefly described my invention, its utility and mode of operation, what I claim and desire to secure by Letters Patent of the United States is—

- 10 1. In a device of the character described, a main submarine, a receiving slip formed in the body thereof, an auxiliary submarine adapted to be moved by its own power longitudinally into the said slip, the said slip 15 having ways and the auxiliary having complementary ways whereby on longitudinal movement of the auxiliary in the slip, the auxiliary is held from vertical movement relative to the main submarine, and a locking 20 device for securing the auxiliary submarine from longitudinal movement.
2. In a device of the character described, a main submarine, a receiving slip formed in the body thereof, an auxiliary submarine 25 adapted to be moved by its own power longitudinally into the said slip, the slip and auxiliary submarine being provided with complementary ways for securing the auxiliary from vertical movement relative to the 30 main submarine, said slip being formed as a recess in the surface of the main submarine and the body thereof at the forward end of the slip being provided with a closable aperture, the said auxiliary submarine having 35 a forwardly protruding member providing a passageway thereinto and adapted to engage in and seal said aperture on movement of the auxiliary into the slip, and means for closing the passageway in the protruding 40 member from the interior of the auxiliary submarine.
3. In a device of the character described, a main submarine, a receiving slip formed in the rear end of the submarine and extending below the upper surface thereof, an auxiliary submarine adapted for operation by its own power and being provided with ways engageable with ways provided in the slip whereby on final longitudinal movement 45 of the auxiliary into the slip the auxiliary is secured from vertical movement relative to the main submarine, the body of the submarine at the forward end of the slip being provided with a closable aperture, a protruding tubular member at the forward end 50 of the auxiliary providing a passageway thereinto, the said protruding member being adapted to engage in water tight relation in the aperture of the main submarine by 55 final longitudinal movement of the auxiliary into the slip, a locking device on the auxiliary, a complementary locking device on the main submarine with which the part on the auxiliary is brought to co-operative relation 60 by movement of the auxiliary into the slip, 65

means for operating the locking device within the auxiliary adapted to draw the auxiliary longitudinally of the slip to final locked position preventing both longitudinal and vertical movement relative to the 70 main submarine.

4. In a device of the character described, in combination with a sea going vessel, a receiving slip formed in the body of the vessel and opening through the surface thereof, the body of the vessel having a closable opening at the forward end of the slip, a submarine operable by its own power having means at the forward end providing a passageway thereinto and adapted to close 80 said opening, locking means on the vessel and submarine respectively brought to co-operative relationship by movement of the submarine longitudinally into the slip, the said locking means being adapted upon locking operation to draw the submarine into the slip to final locked relationship therewith.

5. A sea going vessel having a recess or slip formed in the body thereof open at the 90 end and upper side to allow a second vessel to float thereinto, a submarine operable by its own power adapted to be moved into the recess or slip, interlocking means on the vessel and submarine respectively, the movement of the submarine into the recess bringing the interlocking means into co-operative relationship, means carried by the submarine and co-operative means on the vessel also brought to co-operative relation by 100 movement of the vessel into the slip, means operable from within the submarine to move the auxiliary with said ways and co-operative means into final locked relation.

6. In combination with a sea going vessel 105 provided with a receiving slip of the nature of a recess formed in the body of the vessel open at one end and the upper side, the bottom of the recess being below the normal water level when the main submarine is afloat and being provided with ways, a submarine operable by its own power having complementary ways and adapted when afloat to be moved into the slip with the ways thereon in alignment with the ways in the 110 bottom of the slip, means brought to co-operative relation by movement of the submarine into the slip and operable from within the submarine adapted to draw the submarine to final locked position, the submarine being complementary in form to the vessel when positioned in the slip.

7. In a device of the character described, a main submarine, an auxiliary submarine, a slip formed in the main submarine adapted for receiving the auxiliary submarine, lugs formed in the said slip, an engaging member on the auxiliary submarine, a companion member on the main submarine, means within the auxiliary submarine for 125 130

moving the said engaging member into engagement with the companion member on the main submarine, and means for holding the auxiliary submarine from movement in
5 relation to the main submarine throughout its length, consisting of lugs spaced along the side of the auxiliary submarine.

8. In a device of the character described, a main submarine, an auxiliary submarine,
10 a receiving slip formed in the rear end of the main submarine, an engaging member on the auxiliary submarine, a companion member on the main submarine, means

within the auxiliary submarine for moving the engaging member into engagement with the companion member of the main submarine consisting of a threaded shaft secured to the engaging member on the auxiliary submarine, a nut threaded on the said shaft, and means within the auxiliary submarine 15 for turning the said nut to produce longitudinal movement of the notched engaging member.

In testimony whereof, I sign this specification.

FRANK J. LIESKE.
